Inventor:

George T. Scheel,
By John H. Ross
his Attorney.

UNITED STATES PATENT OFFICE.

GEORGE L. SCHEEL, OF CHICAGO, ILLINOIS.

HAIR FLUFFER AND PERFUMER.

1,252,499.

Specification of Letters Patent. Patented Jan. 8, 1918.

Application filed March 12, 1914. Serial No. 824,122.

To all whom it may concern:

Be it known that I, GEORGE L. SCHEEL, a citizen of the United States, and a resident of the city of Chicago, county of Cook, and State of Illinois, have invented certain new and useful Improvements in Hair Fluffers and Perfumers, of which the following is a specification.

My invention relates to means for fluffing and perfuming hair and is the parent application of my co-pending divisional application, Serial No. 845,558, and the object of my improvement is to provide a simple and effective means of the character mentioned.

Other objects will appear hereinafter.

The invention consists in the combinations and arrangements of parts hereinafter described and claimed.

The invention will be best understood by reference to the accompanying drawing forming a part of this specification, and in which—

Figure 1 is a side elevation of a hair drying, fluffing and perfuming device incorporating my invention;

Fig. 2 is a longitudinal section of the same;

Fig. 3 is an enlarged section taken on line 3—3 in Fig. 1;

Fig. 4 is an enlarged detail section of the perfume holding receptacle and its mounting, and

Fig. 5 is an end view of the perfume holding receptacle, looking in the direction of the arrow in Fig. 4.

The preferred form of construction as illustrated in the drawing comprises a hollow comb 6 having a chamber 7 therein extending through the back thereof. From the chamber 7 is a perforation 8 extending through each of the teeth 9 of said comb.

One end of the back of the comb 6 is closed by means of a plug 10 secured therein. In the chamber 7 is a spider 11 and in said spider 11 and plug 10 is mounted an electric heating element 12. The wires 13 of said heating element are extended through the side of comb 6 and terminate in connecting terminals 14. The terminals 14 are adapted to be connected with any suitable source of electricity, not shown, in order to furnish electrical energy to the heating element 12.

A rubber bulb 15 is connected with the flaring end 16 of the comb 6 and is adapted

to force air through said comb. At one end of the bulb 15 is a nipple 17 internally threaded. On the inner end of nipple 17 is a flap valve 18 adapted to permit air to enter bulb 15 and prevent its escaping therefrom through said nipple.

A tubular perfume holding receptacle 19 is provided with external threads and threaded in the nipple 17. The receptacle 19 is provided with a passage leading therethrough and at each end of said passage is a screen member 20. The screen member 20 may be formed of fine wire gauze, cloth, or any other suitable substance to maintain the perfume in the receptacle. In use a number 70 of receptacles 19 may be furnished with a device, each adapted to hold different kinds of perfume so that the user of the device may by simply unscrewing one receptacle 19 insert another thereby changing the kind 75 of perfume used.

At the back of comb 6 adjacent the spider 11 is an ear 21 to which is pivoted a fluffing member 22. The fluffing member 22 is provided with longitudinal corrugations 23 adapted to fit correspondingly formed corrugations 24 in the back of comb 6. The member 22 is also provided with a handle 25 extended toward the bulb 15 to a position so that the operator may 80 easily operate the fluffing member. The heating element 12, furnishes sufficient heat to cause the curling or fluffing of hair inserted between the member 22 and corrugated portion 24 of the comb. A spring 26 90 normally maintains the corrugated portion 23 and corrugated portion 24 in engagement as will be readily understood.

On the side of comb 6 is secured a projecting arm 27 extending around and spaced 95 from bulb 15. The protector 27 is provided for use in using the fluffer or curler. In operating the latter the protector 27 is engaged by the fingers while the handle 25 is engaged by the thumb of the operator. 100 The provision of member 27 prevents pressing bulb 15 during the operation of the curler or fluffer thereby increasing its life and usefulness.

While I have illustrated and described 105 the preferred form of construction for carrying my invention into effect, this is capable of variation and modification without departing from the spirit of the invention. I, therefore, do not wish to be limited to the 110

precise details of construction set forth, but desire to avail myself of such variations and modifications as come within the scope of the appended claim.

Having described my invention what I claim as new and desire to secure by Letters Patent is:

The combination of a hollow comb with passageways in the teeth thereof and a chamber in communication with said passageways, heating means in said chamber, a rubber bulb arranged at one end of said chamber and provided with a valve inlet, the opposite side of said chamber from said teeth being longitudinally corrugated, a correspondingly corrugated member hingedly mounted upon said comb and coöoperating with the first mentioned corrugated portion,

the last mentioned corrugated member being provided with an operating handle extending upwardly and to a point adjacent said bulb and a fixed handle member secured to the comb and extending upon the opposite side of said bulb from said operating handle whereby the bulb may be operated to force air through the said chamber and teeth or the corrugated portions may be operated independently without compressing the bulb, substantially as described.

In testimony whereof I have signed my name to this specification in the presence of two subscribing witnesses,

GEORGE L. SCHEEL.
